Cook Stove.

Patented Dec. 17. 1834.

NO. 8, 531 X

Dec. 19. 1834.

James Childs, of Merrimack, New Hampshire.
Letters Patent.

The schedule referred to in these Letters Patent and making part of the same, containing a description in the words of the said James Childs, himself, of his improvement in the Cooking Stove.

To all to whom these presents shall come - Be it known that J. James Childs, of Merrimack, in the County of Merrimack, & State of New Hampshire, have invented a new and useful improvement in the Cooking Stove, and that the following is a full and exact description of the construction and operation of the same as improved by me. The bottom of said stove represented by figure I, accompanying this specification, is composed in part of an iron casting whose surface is represented by the section A. forming the hearth, and the section B. three quarters of an inch lower than the surface of A. forming the fire-place of said stove.

The dimensions of said casting are as follows, viz: The greater diameter of the part A. Twenty-four and one half inches & the lesser diameter to the section B. occupied by the fire eleven inches. The greater diameter of the part B. is nine. ten inches, and the lesser to the extremity denoted by the double line 1 a 2. upon Fig. I. sixteen inches, said casting projects at each side beyond the ends of the double line 1 a 2 about two inches and laterally one and a half inch to b & c. in the form included within the double lines upon fig. I.

There is then another casting extending across the extremity of the one described from b to c, with an horizontal surface one inch wide, by which it is riveted to the under side of the main casting, and a perpendicular ring two inches wide with ears upon its lower side for supporting the remaining part of the bottom. The remainder of the stove bottom represented upon fig. I by C is of thick sheet iron, twenty-two inches wide and seventeen and a half inches long exclusive of the circular projection. It is attached to the cast iron part of the bottom, by the ring appendant to it, two inches below the surface of the fire place. The front part and sides of the stove, as far as the cast iron bottom extends, are also composed of iron castings as follows, viz: One a hollow cylindrical segment forming the front part, twelve inches high, and extending

inch each side, beyond the heath of the stove. This contains two doors, eleven and a quarter inches square, forming a double door, represented by fig. III, accompanying this specification. The front part is kept in place by a slight prominence of the edges of the top and bottom of the stove, and by an iron rod passing perpendicularly through them near each end of said casting, secured by a nut and screw at the top of the stove. The sides of the stove to the extremity of the cast iron part of the bottom, are each an iron casting twelve inches high & twelve inches wide, fitted to the front casting of the stove, and secured in the same manner by the edges of the top and bottom, and by iron rods passing perpendicularly through them at 1 and 2, fig. I. From the extreme part of each side casting, extends a wing of cast iron, one and a half inches wide, for enlarging the width of the remaining part of the stove. These wings, or lateral pieces, have tenants at each end, fitting mortises or grooves, in the bottom and top of the stove, by which they are kept in place. There are also ears upon the outer edges of said wings, by which the remaining part of the sides, of the stove, and the back, formed entire, are secured. These are of Russian sheet iron, twelve inches high & of a length and form describing part C. of fig. I. from b. to c.

The back has an aperture, near the middle for a funnel six inches in diameter, and the sides, or one of them, an oven door, and a small aperture under the oven for removing the ashes which may collect in the passage.

The oven extends across the stove twenty-two inches, & is seventeen inches wide, & eight inches high, leaving a space of two inches under it, and four inches above, with a sufficient space behind it, for the passage of the fire to the funnel of the stove. The oven, except the ends which are formed by the sides of the stove, is of thick sheet iron riveted together, and to the sides, and supported also by a piece of iron attached to the back part of the oven at each corner and passing through the top of the stove, secured by a nut & screw. Between the oven and the back of the fire place, is an iron casting, nine inches high, and extending across the stove, in the form described by the line g h i, upon fig I. This casting is raised an inch higher than the top of the oven, and is riveted to it, serving to protect the oven from the immediate action of the fire, and also to increase the draught of the stove.

There is a space between the iron casting attached to the oven and the back

52

of the fire place, represented upon fig. 3, by the space between the line 1 a 2, and
high i, for the passage of fire under and above the oven of the stove to the fun-
nel. This space is one and three quarter inches wide in the middle at h a,
and about two inches at either end. The fire is admitted to it through an hor-
izontal aperture in the back of the fire place, two inches from the top of the
stove seventeen inches long, by two inches wide, and is divided upon its passage
through said aperture, a part passing over the oven, and a part under it, to the
funnel. The fire may, however, be made to pass entirely over the oven by means
of a damper fire at the back part of the stove. The back of the fire place is
an iron casting represented by fig. IV, twelve inches high & nineteen inches
long. It rests upon the extremity of the cast iron part of the bottom, in the
form of a curve describing the line 1 a 2, upon fig. I. and is kept in place
by the iron rods at the points marked 1/2, and by slight grooves or proje-
tions from the sides, and top of the stove. The top of the stove is a single
iron casting with a level surface for kettles, and other furniture, repre-
sented by the circle, upon fig. V, accompanying this specification.

It corresponds in its dimensions with the bottom exclusive of the hearth. The
orifices upon the top are closed by cast iron lids, with bars of wire, the larger
orifices having a lid within a lid, as represented by the circles upon fig. V, for
varying the size of the orifice, as convenience may require.

Upon petitioners claims as an invention made by himself, and improvement
in the cooking stove, the passage of the fire by a single horizontal aperture
through the back of the fire place, and its equal division & draught under
and over the oven, by the elevation of the cast iron back of the oven as
high as the middle of said aperture, and above the top of the oven, thus
making the space, remote from the fireplace, both under & above the oven
larger than at the aperture, and thereby improving the draft of the stove,
also the enlargement of the back part of the stove, by the perpendicular wing
at the bottom, and the wings at the sides, whereby a larger oven is made
than in any other stove of equal size & other conveniences, and is more
uniformly heated by being on a level with the fire place, allowing the
fire also, to act more directly upon whatever is placed on the orifice at
the top, than in any other stove. In testimony, that the above is a true

Specification of my said instrument, as above described, I have hereunto
set my hand this twenty-second day of November, anno Domini one
thousand eight hundred and thirty-four.

Witness,

Sam'l Smith
Calvin Smith

James Childs
